UNITED STATES PATENT OFFICE.

HARRY Y. ARMSTRONG, OF SPRINGFIELD, MASSACHUSETTS, ASSIGNOR TO PACKAGE MACHINERY COMPANY, OF SPRINGFIELD, MASSACHUSETTS, A CORPORATION OF MASSACHUSETTS.

WRAPPING-MACHINE.

1,280,364.

Specification of Letters Patent. Patented Oct. 1, 1918.

Application filed April 16, 1915. Serial No. 21,739.

To all whom it may concern:

Be it known that I, HARRY Y. ARMSTRONG, a citizen of the United States, residing at Springfield, in the county of Hampden and 5 State of Massachusetts, have invented certain Improvements in Wrapping-Machines, of which the following description, in connection with the accompanying drawings, is a specification, like reference characters on 10 the drawings indicating like parts in the several figures.

A very common method of wrapping articles consists in folding a wrapper about an article to form a tube with its longest dimensions extending in the direction of the length of the article, and then making tucks in the wrapper at the opposite ends of the article to complete the wrapping operation. Machines of the rotary type are much used 15 in wrapping packages in this manner because of their simplicity and high speed. While these machines operate very satisfactorily on small packages or packages in which the longitudinal edge flaps of the 20 wrapper are folded against one side of the package, as distinguished from its edge, difficulties are experienced in attempting to wrap large packages when it is desired to have the longitudinal flaps folded on one 25 edge of the package, or wherever it is desired to have these flaps folded against a wide surface of a package while it is in the tumble box or wheel of the machine.

The present invention provides a machine 30 in which this difficulty is overcome and in which the overlapping flaps, in addition to being folded properly, may also be heat sealed while in the tumble box. The invention also provides novel folding devices 35 which are applicable to other types of wrapping machines than that specifically mentioned above. These and other novel features of the invention will be readily understood from the following description of one 40 embodiment thereof, reference being made to the accompanying drawings, in which—

Figure 1 is a vertical, sectional view 45 through a wrapping machine showing in elevation mechanism embodying the present invention;

Fig. 2 is a perspective view of the wrapper 50 engaging face of one of the folders;

Figs. 3 and 4 are fragmentary views showing different positions of the folders that make the longitudinal edge fold on a package; 55

Fig. 5 is a side elevation showing a detail of construction; and

Figs. 6 to 9, inclusive, are perspective views of a package showing the successive 60 steps in the process of wrapping it.

The drawings show a well known type of wrapping machine of the same general organization as that disclosed in the application of M. B. Ferguson, Ser. No. 607,592, 65 filed Feb. 9, 1911. This machine is of the rotary type; that is, it includes a rotary wheel or tumble box having one or more pockets in which an article is positioned while certain of the wrapping operations are 70 being performed on it. In the present instance the tumble box, which is indicated at 2, is provided with four pockets. This machine, as is well understood by those skilled in this art, is so arranged that the packages 75 are introduced into the tumble box one at a time, each package picking up a wrapper while it is being carried into the tumble box. In the arrangement shown the paper feeding mechanism is designed to feed the wrappers 80 one at a time in front of the tumble box 2, and a plunger 3 then forces a package into engagement with the wrapper and into the pocket positioned at *a*, Fig. 1, the construction of the pocket being such that when the 85 package is finally deposited in the pocket, the wrapper will be folded about three sides of it in the form indicated in Fig. 6. The paper feeding mechanism will, of course, be designed to feed the kind of wrapping material required for the particular package to be wrapped. It is contemplated in the present machine that a wrapper impregnated with paraffin or other waxy material may be used so that it can be heat sealed on the 90 package. A package having been introduced into a pocket of the tumble box at *a*, Fig. 1, the tumble box is next moved ninety 95 degrees to bring the pocket which has just received the package into the position *b*, where the edge flaps of the wrapper are folded down, and the pocket is then carried into the position *c* where a plunger, carried by the tumble box, pushes the package into

90

95

100

a folding chute 4 that makes the remaining end folds on the package and leaves it in the form shown in Fig. 9.

This invention is particularly concerned 5 with the mechanism that folds two longitudinal edge flaps *d* and *e* against one face of the package as they are shown in Fig. 8. Assuming the package to have just been moved into the position *b*, Fig. 1, these two 10 longitudinal flaps *d* and *e* will be left standing up, as shown in Figs. 3 and 6. The walls of the pocket, of course, hold the wrapper about three sides of the package. The flap *d* is folded over on to the remaining 15 side of the package by means of a folder 5 supported by a pair of arms 6 fast on a rock shaft 7 mounted above the tumble box and operated by connections with a cam 8 which is driven from the main shaft of the 20 machine. The folder 5 is pivoted on the arms 6 so that it can have a rocking movement, this movement being limited, however, by a pair of set screws 9 which are threaded through lugs rigid with the folder and bear 25 against the respective arms 6. As shown in the drawings, the folder extends for a considerable distance at the side of its pivot toward the tumble box; and two coiled springs 10, interposed between the arms 6 and lugs 30 rigid with the folder 5, tend to tip this extended side of the folder toward the tumble box.

The other flap *e* of the wrapper is folded down on the flap *d* by means of a heated 35 folder or hot box 11 pivotally mounted between two arms 12 which depend from but are fast to a rock shaft 7 supported in the machine frame directly above the tumble box. Another pair of arms 13, extending 40 parallel to the arms 12, are fastened to a rock shaft parallel to the shaft 7; and the individuals of each pair of arms 12 and 13 at the opposite sides of the tumble box are connected by two horizontal links 15, each 45 pivoted to the lower ends of the respective arms. One of the arms 13 is extended beyond the rock shaft 14 and is connected by a rod 16 to a cam follower operated by a cam 17 that rotates with the cam 8. This mechanism 50 swings the folder or hot box 11 from the position shown in Fig. 1 to that shown in Figs. 3 and 4 and back again.

In order to allow the folder 11 to adjust 55 itself to the face of the package on which it makes a fold, a lost motion connection is provided between it and the arms 12; that is, the pivots which project from the opposite ends of the folder extend through elongated holes 18 (see Fig. 5) in the arms 12 and 60 then enter closely fitting holes in the ends of the links 15. This arrangement allows the package to raise the folder with reference to the arms 12 and also enables the folder to rock freely to adjust itself to the 65 face of the package on which it rests. A

weight 20, adjustable in the ends of the links opposite the ends attached to the arms 12, counterbalances the weight of the folder 11 and thus enables the package to move it easily while it is in contact therewith. 70

Heat may be supplied to the folder 11 in any convenient manner but in the arrangement shown a flexible pipe 21 is provided to deliver steam to the chamber in the folder, a similar pipe carrying the steam away from 75 the other end of the folder. The folder or hot box 11 thus is continuously heated in all positions and is maintained at substantially a uniform temperature.

As soon as the tumble box moves into the 80 position *b*, Fig. 1, the folder 5 is swung into the position in which it is shown in Fig. 4, thus laying down the flap *d* on the edge face of the package. The springs 10 tip this folder in such a direction that its forward edge first strikes the edge face of the package and as the folder wipes inwardly over this face, the springs yield to permit the folder to rock toward a position parallel with said face. This folder pauses while 90 the folder 11 is swung toward the position in which it is shown in Fig. 1, the folder 5 retiring just fast enough to keep out of contact with the folder 11 so as to hold the flap *d* in place while the flap *e* is being folded 95 down on it by the member 11. In order to reduce the friction between the face of the folder 5 and wrapper and thus prevent the folder from wrinkling up the wrapper as it retires, the face of the folder is provided 100 with several ridges 5', Fig. 2. This construction reduces very greatly the drag of the folder on the wrapper flap and prevents the action just referred to.

The folder 11, as it rests on the edge face 105 of the package, melts the wax in the overlapping flaps *e* and *d*. The tumbler box is now advanced from the position *b* to the position *c*, Fig. 1, thus carrying the edge of the package under a curved brush 23 which 110 yieldingly holds the flaps *d* and *e* in contact with each other and at the same time exerts a cooling action on the wax, thus causing the two flaps to adhere to each other.

In order to move the brush out of the 115 path of the folder 11, the lower end of this brush is pivoted to the machine frame at 24 and its upper end is connected by two links 25, one on each side, to the respective pivots that join the arms 13 to the links 15. This 120 mechanism compels the upper end of the brush to swing with the folder 11. The folder 11 remains stationary after being swung into the position in which it appears in Fig. 1 until the tumble box has carried 125 the package about one-half the length of the brush 23, at which time the folder begins to retire to the position in which it is shown in Fig. 3, so as not to interfere with the proper positioning of the next package 130

for the operation of the folders 5 and 11. This retiring movement is short, as will be evident from an inspection of Fig. 3, and does not carry the brush 23 far enough to 5 interfere in any way with its action on the flaps *d* and *e*. By the time the package has reached the position *c* in readiness to be pushed into the folding chute 4, the flaps will have cooled sufficiently to cause the wax 10 which they carry to seal them securely together. The end folds are made in the wrapper by the folders of the chute 4 and the packages are then carried away from the tail of the machine through end sealing 15 mechanism which heat seals the end folds in the same way that the longitudinal folds have been sealed.

The machine shown in the drawings is designed to wrap a very large package and 20 to make the overlapping longitudinal fold on the edge of the package as distinguished from its side. The folding mechanism provided by this invention folds the wrapper tightly about the package and seals it in 25 this condition. The construction of the folders by which they are enabled to adjust themselves to the face of the package materially contributes to this end, since it enables them to hold the wrapper flaps firmly 30 against the face of the package, which otherwise could not be done because of the width of the face of the package on which these flaps are folded. It is obvious that the same mechanism could be used success- 35 fully on packages in which it was desirable to make the fold on a wide face of the package, whether this happened to be the edge or side face.

Having thus described my invention, what 40 I claim as new and desire to secure by Letters Patent of the United States is:—

1. In a wrapping machine, the combination with a tumble box and mechanism for introducing packages one at a time into the 45 pockets of the tumble box with a waxed wrapper folded about three sides of each package, of means operative to fold and seal together the longitudinal edge flaps of the wrapper while the package is in the 50 tumble box, said means including a heated device operative to melt the wax on the overlapping portions of said wrapper flaps, and a movable support for said heated device on which the device is pivotally 55 mounted.

2. In a wrapping machine, the combination with a tumble box and mechanism for introducing packages one at a time into the tumble box with a wrapper folded about 60 three sides of each package, of folders arranged to be moved alternately over the remaining face of the package to fold the longitudinal edge flaps of the wrapper against said face while the package is in the tumble 65 box, means for operating said folders, and a

curved brush arranged to hold said flaps of the wrapper in their folded position while the tumble box carries the package away from the folders, the end of said brush adjacent to the folders being connected to the 70 folder that makes the final fold in the wrapper so that it will be moved by the movement of the folder.

3. In a wrapping machine, the combination with a tumble box, means for rotating 75 it and mechanism for introducing packages one at a time into the pockets of the tumble box with a wrapper folded about three sides of each package, of means operative to fold and seal together the longitudinal edge flaps 80 of the wrapper while the package is in the tumble box, said means including a heat device mounted for movement toward and from the face of the package on which said flaps are folded, and a movably mounted 85 curved brush operative to press the overlapping flaps together while the tumble box rotates.

4. In a wrapping machine, the combination with a tumble box and mechanism for 90 introducing packages one at a time into the pockets of said tumble box with a waxed wrapper folded about three sides of each package, of movable folders operative to fold the longitudinal edge flaps of the 95 wrapper against the remaining face of the package while it is in said tumble box, the last of said folders to engage the wrapper being constructed and arranged to have heat supplied constantly thereto in all positions 100 thereof, and flexible cooling means operative to hold said overlapping flaps in contact with each other while the tumble box moves the package away from said heated folder.

5. In a wrapping machine, the combination with a tumble box, and mechanism for 105 introducing packages one at a time into the pockets of said tumble box with a wrapper folded about three sides of each package, of folders for folding the longitudinal edge 110 flaps of the wrapper against the remaining side of said package while it is in said tumble box, and means for moving said folders alternately over said remaining side, said folders being mounted for movement while 115 in engagement with the package to adjust themselves to the face of the package with which they are in contact.

6. In a wrapping machine, the combination with a tumble box and mechanism for 120 introducing packages one at a time into the tumble box with a wrapper folded about three sides of each package, of folders arranged to be moved alternately over the remaining face of the package to fold the longitudinal edge flaps of the wrapper against 125 said face while the package is in the tumble box, means for operating said folders, a curved brush operative to hold said flaps of the wrapper against said face of the package 130

while the tumble box carries the package away from the folders, and means for moving the end of said brush adjacent to said folders.

- 5 7. In a wrapping machine, the combination with means for partially folding a wrapper about a package, of a folder operative to make an additional fold in said wrapper, said folder having ridges extending parallel to the direction of relative move-

ment of the folder and package and serving to reduce the friction between the folder and the wrapper.

In testimony whereof I have signed my name to this specification in the presence of 15 two subscribing witnesses.
